HERMAN E. GRAHAM, OF MARION, INDIANA, ASSIGNOR TO CHICAGO RAILWAY EQUIPMENT COMPANY, OF CHICAGO, ILLINOIS, A CORPORATION OF ILLINOIS

ANNEALING POT

Application filed November 14, 1931. Serial No. 575,100.

This invention relates to pots for use in an annealing oven.

Annealing pots of the present type are usually stacked one above the other in the annealing oven and each pot is provided with a top flange offset outwardly and having an inner ledge for receiving the bottom of the superimposed pot. The joints are "muddled" before heating in order to make the pots air tight. Where the mudding is done before the pots are slid into the oven on the charger, the rough floor of the oven frequently causes injury to the muddled joint, which must be repaired. Moreover, after the charge has been dumped considerable time and labor is required in cleaning up the pots, ovens, and floor of the annealing department.

Also the pots at present in use have a tendency to bulge outwardly during heating and gradually assume a circular shape. This decreases the capacity of the pots and makes increasingly difficult the sealing of the joints between the pots due to irregularities. Also the floor of the pots tend to sag due to the weight of the metal being annealed.

One object of the present invention is to provide an annealing pot which will overcome the above disadvantages and which will last longer than pots at present in use.

Another object is to provide a pot which, when stacked with other pots, will assist in maintaining the original shaping of the next lower pot, and which will form a desirably tight joint with the adjacent pots without the use of mud or fire clay.

Another object is to provide means for adequately supporting the floors of the stacked pots.

These objects and others are attained in the structure illustrated in the accompanying drawings in which—

Figure 1 is a top view of the pot.

Figure 2 is in part a side view of the same and in part a vertical longitudinal section and also showing a portion of a superimposed pot.

Figure 3 is an end view of the pot.

Figures 4 to 8, inclusive, are fragmentary vertical transverse sections showing modified forms of pots stacked one above the other.

My improved annealing pot is substan-

tially rectangular in shape and includes side walls 1 and end walls 2 having an outward horizontal flange 3 extending entirely around the pot near the top of the walls thereof. The walls extend upwardly a short distance beyond flange 3 to form an upright flange or rib 4. The side and end walls are further braced by ribs 5 and 6 on the outside of the pot, ribs 6 merging with carrier trunnion bearings 8.

Bottom 9 of the pot extends outwardly a short distance beyond the upright walls thereof and is provided with a depending flange 10. Bottom 9 is braced on the underside by diagonal ribs 11.

The outer ends of ribs 11 are substantially flush with the inner surface of walls 1 and 2, and the inner surface of flange 10 is flush with the outer surface of flange 4. Thus, when the pots are stacked one above the other, top flange 4 of each pot will fit snugly inside of bottom flange 10 of the next higher pot and the bottom of flange 10 of the latter pot will rest upon the top of flange 3 of the lower pot.

The pot is also provided with a central upright post 12 projecting from the center of the floor 9 which extends substantially the entire depth of the pot and is long enough to seat against the boss 13 at the intersection of ribs 11 of a superimposed pot in a stack. Post 12 supports the floor of the upper pot and prevents sagging. This post may be formed integral with the floor of the pot, as shown, or may be otherwise secured to the floor.

A cover (not shown) is provided for the topmost pot in the stack which has a depending flange corresponding with flange 10. The pots when stacked are desirably tight and do not require mudding around the joints either before or after insertion into the oven. Moreover, the contact of the lowermost pot, or the charger, with the rough oven floor will cause the joints to settle more tightly together.

In Figure 4 a separately formed bottom member 12 has parallel ribs 13 and 14 extending around the upper and lower surfaces thereof and forming grooves for receiving the adjacent edges of the walls 15 and 16 of the stacked pots. The floor member also has

centrally located bosses 17 and 18 and sockets 19 and 20 for receiving the ends of posts 21. Each post is of sufficient length to extend from the upper socket 19 of one floor member to the lower socket 20 of the next higher floor member in a stack and serves to support the latter member.

In Figure 5, the floor member 22 is formed integrally with the walls of the pot and has 10 parallel ribs 23 extending around the lower surface thereof for snugly receiving the upper edges of the walls of the next lower pot. A horizontal flange 24 extends around the pot near the top thereof. Member 22 also has 15 central bosses 25 and 26 and sockets 27 and 28 for seating posts 29.

In Figure 6 a bead 29 surrounds the lower edge of the pot and the upper edge of the pot is provided with a complementary recess 30 20 for receiving bead 29 of the next higher pot in a stack.

In Figures 7 and 8 horizontal flanges, as 31 and 32 in Figure 7, surround the lower and upper edges of the pot respectively. The 25 lower surface of the bottom flange and the upper surface of the top flange are provided with complementary elements, as 33 and 34, respectively, each of which cooperates with the complementary element of the adjacent 30 pot in a stack to form an air-tight joint therewith. In Figure 7 these elements are substantially circular in section; and in Figure 8 the interengaging elements 35 and 36 are triangular in section.

35 Due to the interlocking walls of adjacent pots, each maintains its rectangular shaping considerably longer than old style pots. This feature of the invention, as well as the location of the bracing ribs on the outside instead of on the inside, as is the usual practice 40 at present, affords the maximum capacity while at the same time resulting in ample draft space around the walls of the oven. Furthermore, since the use of muddled joints 45 is unnecessary, considerable time and labor is saved both in preparing the stacked pots for heating and in cleaning up the annealing department after dumping.

Obviously, the structure illustrated may be 50 varied as to certain details without departing from the spirit of the invention, and the exclusive use of all such modifications as come within the scope of the appended claims is contemplated.

55 What is claimed is:

1. In an annealing pot, side and end walls, a horizontal flange surrounding the pot at the tops of said walls, an upright flange extending above said horizontal flange, and a 60 depending flange surrounding said pot at the bottom of said walls, said pot being arranged to be stacked with other similar pots, and said depending flange being shaped to fit snugly over the top flange of the next lower 65 pot in a stack and seat against the horizontal

top flange of said latter pot, said depending flange being arranged to cooperate with the top and horizontal flanges of said next lower pot in a stack to form a desirably tight joint and assist in preventing bulging of said lower 70 pot.

2. In an annealing pot, side walls, a floor element, and a post projecting upwardly from said element, said pot being arranged to be stacked with other similar pots, and said post 75 being of a height to engage the floor of the next higher pot in a stack and support the same.

3. In an annealing pot substantially upright walls, a floor element, bracing ribs beneath said floor, said ribs intersecting in a boss, and a post projecting upwardly from the portion of said floor directly above said boss, said pot being arranged to be stacked with other similar pots, and said post being 80 of sufficient length to seat against the boss under the floor of the superimposed pot and support said floor.

4. In an annealing pot substantially upright walls, a floor, depending flanges surrounding said pot beneath said floor, and bracing ribs on the under surface of said floor, said pot being arranged to be stacked with other similar pots, said depending flange being shaped to fit snugly over the top of the next lower pot in a stack and outside the walls thereof, and there being sufficient space between said ribs and said depending flange to permit the insertion therebetween of the tops of the walls of said next lower pot.

5. In combination, a plurality of annealing pots stacked one above the other, said pots each including side walls, a floor, and a peripheral flange depending from said floor, said flange fitting snugly over and outside of the top of the next lower pot, and said flange and said floor serving to assist in maintaining the original shape of said lower pot during heating.

6. In combination, a plurality of annealing pots stacked one above the other, said pots being similar and each including upright walls, a floor, a depending flange surrounding said pot beneath said floor, and a post extending upwardly from the center of said floor, said flange being shaped to fit snugly over and outside of the top of the next lower pot and form a desirably tight joint therewith, and said post engaging the floor of the next higher pot and supporting the same, all of the depending flanges and posts in the stack assisting in maintaining the original shaping of said pots during heating.

7. In an annealing pot, substantially upright walls, and a separately formed closure member having a peripheral groove extending around a surface thereof and adapted to snugly receive the edges of said walls whereby a desirably tight joint will be formed without the use of filler material.

8. In an annealing pot, side walls, a separately formed floor member having elements extending around the upper surface thereof and adapted to snugly receive the lower edges of said walls, and having a central socket, said pot being adapted to be stacked with other similar pots, and a post shaped to be inserted in said socket and to support the floor of the next higher pot in a stack.
9. In an annealing pot, substantially upright walls, a floor member having parallel ribs on the upper and lower surface thereof forming grooves and central sockets on said surfaces, said pot being adapted to be stacked with other similar pots, and said upper and lower grooves being shaped, respectively, to snugly receive the lower edges of said walls and the upper edges of the walls of the next lower pot in a stack, and a post shaped to seat in said upper socket and to extend into the lower socket of the next higher floor member in a stack.
10. In an annealing pot, substantially upright walls and a floor member having parallel ribs on the under surface thereof forming a groove surrounding the same, said pot being adapted to be stacked with other similar pots and said groove being shaped to snugly receive the top edges of the walls of the next lower pot in a stack and to prevent bulging of said lower pot.
11. In an annealing pot, substantially upright walls and a floor member, there being substantially horizontal surfaces surrounding the top and bottom edges of said walls, respectively, said pot being adapted to be stacked with other similar pots, and complementary interengaging elements on said surfaces, each of said elements being arranged to cooperate with the complementary element on the adjacent pot in a stack to form a desirably tight joint therewith and assist in maintaining the original shaping of the walls thereof.
12. An annealing pot having substantially upright walls, said pot being adapted to be stacked with other similar pots and the inner surfaces of said walls at the bottom closely conforming in size and shape with the outer surfaces of the same at the top whereby a desirably tight joint will be formed between stacked pots and the walls of each superimposed pot in a stack will assist in maintaining the shaping of the next lower pot.
13. In combination, an annealing pot having walls open at at least one end, said pot being adapted to be stacked with other similar pots, and a closure member for said open end having peripheral groove forming elements on its faces disposed to snugly receive the edges of adjacent pots in a stack and to form therewith desirably tight joints without filler material and to assist in maintaining the shaping of said pots.
14. In an annealing pot, upright walls, and a horizontal flange surrounding said walls adjacent one end, said flange being adapted to seat against the edge of an adjacent pot in a stack and the tops of said walls being shaped to fit snugly inside the bottom portions of the walls of the next higher pot and to cooperate with said flange and said portions in forming a desirably tight joint, the walls of said higher pot assisting in preventing bulging of said first-mentioned pot and thereby maintaining the tightness of said joint.
15. In an annealing pot, side walls, an element connecting the lower portions of said walls and preventing bulging of said walls, said pot being adapted to be stacked with other similar pots and said walls at the top being shaped to fit snugly inside the lower portions of the walls of the next higher pot in a stack whereby said element also prevents bulging of the walls of said lower pot.
- In testimony whereof I hereunto affix my signature this 30 day of October, 1931.
- HERMAN E. GRAHAM.
